BLADE HANDLE

Pierce W. Koontz, Glendale, Calif.

Application July 19, 1946, Serial No. 684,985

4 Claims. (Cl. 279—87)

1

This invention relates to a device for supporting articles such as knife blades, spatulas and the like.

It is the object of the invention to provide a simple, light, and inexpensive device in which such articles may be rigidly and permanently mounted. To this end, the invention consists in the combinations hereinafter described in detail and a preferred form of the invention is illustrated in the accompanying drawings, of which:

Fig. 1 is a side view of a device embodying the invention;

Fig. 2 is a corresponding view with a portion of the device broken away;

Fig. 3 is a side view taken at right angles to the view of Fig. 1;

Fig. 4 is like Fig. 3 but with a portion thereof broken away in order to expose the interior construction thereof; and

Fig. 5 is an end view of the device.

A certain type of blade holder is found on the market at the present time and has become quite popular. It consists of a steel handle, the end of which is slotted to receive the blade of a knife or the like, and this blade is rigidly secured in the slot by means of a spot welding operation. The objection to this type of holder is its weight, and when it is considered that such devices are used by engravers and others performing very delicate operations it is readily appreciated that such heavy handles are undesirable.

Such objection may be overcome by utilizing a handle made from suitable light material, such as an aluminum alloy or some type of magnesium alloy, but because such handles do not lend themselves to spot welding operations, it becomes necessary to find other means of fastening the blade therein, and such means will now be described.

The device of the invention illustrated in the drawings comprises a handle 1, in one end of which is formed a cylindrical recess 2, of a size to receive a pair of semi-cylindrical clamping members 3, 4, between which the blade 5 is placed, whereupon these members together with the blade are driven into the recess of the handle.

The inner ends of these members, 6, 7, are shown slightly tapered in order to facilitate in-

2

sertion of the members and the blade into the handle. When the parts are in this manner driven into the handle, it is found that the blade becomes rigidly anchored therein and will not become loose or separated therefrom. The ends of the members should extend beyond the end of the handle, as shown, in order to stiffen the blade at this point and may project further than shown if preferred.

- 10 It is noticed that the shank 8 of the blade is somewhat reduced in width thereby to provide shoulders 9, 10 which, when the parts are driven into the handle, lodge within a slot 11 in the end thereof. When the blade is in this manner guided within the slot 11, it is found that it is not possible to twist the clamping members 6, 7 within the recess of the handle and the blade is held so rigidly in position that it will withstand any pressure tending to dislodge it.
- 15 From the foregoing, it is seen that I have provided a simple and inexpensive device capable of supporting articles such as above referred to over long periods of time without danger of such articles becoming loosened or dislodged.

25 I claim:

1. A blade holder consisting of an elongated handle having a cylindrical recess in one end thereof, in combination with a pair of semi-cylindrical clamping members, and a blade mountable between said members, the members together with said blade being insertable into the recess in the end of the handle and driven into the recess to lock the blade firmly in position.
- 30 2. A blade holder comprising a handle having a cylindrical recess in one end thereof and a transverse slot at the entrance to said recess, in combination with a pair of cylindrical clamping members, and a blade, said blade having a shouldered shank of a width to fill the space between the said two members, the members together with the blade being insertable into said recess and driven into the recess until the shoulder formed between the shank of said blade and the blade proper becomes lodged within said transverse slot.
- 35 3. A blade holder comprising, a handle having a cylindrical recess in one end thereof and a transverse slot at the entrance to said recess, in combination with a pair of cylindrical clamp-
- 40

- 50

ing members, and a blade, said blade having a shouldered shank of a width to fill the space between the said two members, the members together with the blade being insertable into said recess and driven into the recess until the shoulder formed between the shank of said blade and the blade proper becomes lodged within said transverse slot, the inner ends of said members being slightly tapered in order to facilitate insertion thereof into the handle.

4. A blade holder comprising a handle recessed at one end thereof, a pair of semi-cylindrical clamping members, and a blade held between said members to be driven with the members into said recess, the members projecting beyond the end of the handle in order to stiffen the blade at this point.
